UNITED STATES PATENT OFFICE.

WILLIAM F. BACH, OF CHICAGO, ILLINOIS.

GATE-OPERATING MECHANISM.

1,205,423.

Specification of Letters Patent.

Patented Nov. 21, 1916.

Application filed July 1, 1910. Serial No. 569,939.

To all whom it may concern:

Be it known that I, WILLIAM F. BACH, a citizen of the United States, and a resident of Chicago, in the county of Cook and State 5 of Illinois, have invented certain new and useful Improvements in Gate-Operating Mechanisms, of which the following is a specification.

My present invention relates to gate operating mechanisms in general, and more particularly to mechanism for controlling the opening of gates affording access to elevator cars and the shafts wherein they run. It contemplates especially the provision of 10 an improved mechanism for successively opening and closing the gate, as the elevator approaches and leaves the corresponding floors in its ascent or descent, operable at the will of the elevator conductor and not solely 15 according to the movement of the elevator car, together with automatically operable means for respectively unlatching and latching the gate when the opening mechanism is moved into operative position.

20 The principal objects of my present invention are the provision of a gate of the character specified wherein the ascent or descent of the car does not of itself open the gates to the hatchway, but one wherein the 25 gate operating mechanism may be readily thrown into operative position so as to cause the movement of the car to open the gate; the provision of improved mechanism of the character referred to operable by slight 30 movement of a treadle, leaving the operator's hands free for control of the car, and one which automatically restores itself to inoperative position; the provision of such mechanism of a simplified form which is in- 35 35 expensive in construction, unlikely to become out of order, positive and certain in its operation, and having means for the prevention of interference of the parts carried by the car and certain parts stationary in 40 the shaft or hatchway; the provision of improved means for preventing the gate from sticking or becoming wedged in the act of being raised or lowered; the provision of improved means for automatically locking the 45 gate against opening save when opened by the movement of the mechanism carried by the car and upon the approach of the car; together with certain other objects which will hereinafter appear.

50 In the so-called automatically operating elevator gates in common use at this day, as

known to me for the greater part, the gates at each floor allowing access to the hatchway, automatically rise and fall successively each time the car approaches the floors on 60 which they are located, whether ascending or descending, and as a result, the gates are given a great deal of unnecessary movement, thereby subjecting them to undue wear and tear and materially increasing the 65 amount of repair required to keep them in operative condition; moreover, such gates as have come under my observation frequently become out of order owing to failure of the parts carried by the car properly to engage 70 the parts mounted in the hatchway, striking them improperly with consequent breakage and displacement and furthermore many accidents happen owing to the lack of adequate latching devices to prevent tampering 75 with the gates by unauthorized persons.

In attaining the advantages above mentioned in overcoming the disadvantages referred to, and in securing certain further benefits to be below more fully disclosed, I 80 have provided the construction illustrated in the accompanying drawings, wherein—

Figure 1 is a perspective elevational view of an elevator hatchway, car and gate, whereupon is mounted a preferred embodiment of my improved gate operating mechanism, the mechanism for operating the gates being here shown in operative position and the gate partly opened; Fig. 2 is an enlarged perspective view of a detail of construction; Fig. 3 is a side elevational view of the construction of Fig. 1 viewed from a point external to the car, the gate operating mechanism being shown in inoperative position; Fig. 4 is an elevational view of the operating mechanism of Figs. 1 and 3, viewed from within the car, the gate being shown in fully opened position, and Fig. 5 is an elevational view partly in section, the opening of the gate about to begin, and the latch being in inoperative position, and the gate free to rise; Fig. 6 is a view similar to that of Fig. 5 the latch being shown in operative position, and the gate locked in closed position.

Referring now more particularly to Fig. 1 of the drawings, it will be noted that my invention comprises essentially two co-operative mechanisms, the one "A", the elements carried adjacent each floor for opening and closing the gates which normally prevent access to the shaft or hatchway 10, and the

other the actuating mechanism "B" carried by the car 11, whereby the operating mechanism "A" is actuated at the will of the elevator conductor, to which may be added a 5 third, "C" the latching devices coöperating with the elements A and operable by their movements.

Referring first to the gate operating mechanism "A" it will be observed that the 10 gate 12 is preferably mounted in guideways 13 and lifted and lowered by means of ropes 14 and 15 attached adjacent each end of the gate, the rope 14 passing over a single sheave 16 and both ropes over a double sheave 17, below which the ropes 14 and 15 are joined as indicated at 18, whence they are continued as a single rope 19, passing over a sheave 20, thence over a sheave 21 (Fig. 2), a sheave 22 (Fig. 1) arranged at an 15 angle to the sheaves 20 and 21 in order to avoid twisting of the rope 19, thence over a sheave 23 mounted on the shaft 24 which likewise carries the sheave 21 and finally over a sheave 25, a counter weight 26 being 20 attached to the end of the rope to keep it taut at all times, and thereby avoid kinking or displacement of the rope from the grooves of the sheaves. As will be observed on a comparison of Fig. 1 with Figs. 3 and 25 30 35 40 45 50 55 60 65 70 75 80 85 90 95 100 105 110 115 120 125 130 135 140 145 150 155 160 165 170 175 180 185 190 195 200 205 210 Having thus described my invention and illustrated its use, what I claim as new and desire to secure by Letters Patent is the following:

- 5 1. The combination with an elevator car movable in a shaft, a gate, and actuating mechanism carried by the car, of gate operating mechanism comprising a cable, a pair of stationary sheaves, and a moving cage carrying a pair of sheaves and adapted for engaging said actuating mechanism, and a fifth sheave arranged between said pairs of sheaves, said cable engaging said five sheaves, and the fifth sheave being arranged 10 at an angle to said several pairs of sheaves, whereby twisting of the cable is avoided.
- 15 2. The combination with an elevator car movable in a shaft, a gate, means for operating the gate including a striking member, and means operable by the movement of the car for actuating said operating means, of a substantially vertical rack and a latch normally disposed at an angle to said rack for locking the gate adapted to be held in engagement with each other in one position, said striking member being movable by the movement of the gate operating means and adapted to move the latch out of engagement with the rack when the gate operating 20 means is operated by the movement of the car.
- 25 3. The combination with an elevator car movable in a shaft, a gate, means for operating the gate, including a striking member and means operable by the movement of the car for actuating said operating means, of a coöperating rack and latch for locking the gate, said latch having a weighted arm for holding the latch in engagement with the rack in one position, and said striking member being operable by the movement of the gate operating means and adapted to move the latch out of engagement with the rack when the gate operating means is operated by the movement of the car. 30
- 35 4. The combination with an elevator car movable in a shaft, a gate, means for operating the gate including a striking member, and means operable by the movement of the car for actuating said operating means, of a coöperating rack and latch for locking the gate, said latch having a weighted arm for holding the latch in engagement with the rack in one position, and said striking member being operable by the movement of the gate operating means and adapted to move the latch out of engagement with the rack when the gate operating means is operated by the movement of the car, said weighted arm being located in the path of movement 40 of said latch operating means.
- 45 5. The combination with an elevator car movable in a shaft, a gate, means for operating the gate including a striking member, and means operable by the movement of the car for actuating said operating means, of a coöperating rack and latch for locking the gate, said latch having a weighted arm for holding the latch in engagement with the rack in one position, and said striking member being operable by the movement of the gate operating means and adapted to move the latch out of engagement with the rack when the gate operating means is operated by the movement of the car, said weighted arm being located in the path of movement 50 of said latch operating means.
- 55 6. The combination with an elevator car movable in a shaft, a gate, means for operating the gate including a striking member, and means operable by the movement of the car for actuating said operating means, of a coöperating rack and latch for locking the gate, said latch having a weighted arm for holding the latch in engagement with the rack in one position, and said striking member being operable by the movement of the gate operating means and adapted to move the latch out of engagement with the rack when the gate operating means is operated by the movement of the car, said weighted arm being located in the path of movement 60 of said latch operating means.

In testimony whereof I have hereunder signed my name in the presence of the two subscribed witnesses.

WILLIAM F. BACH.
